U. S. PATENT OFFICE.

No. 729.

1861.

WHOLE No. 31,733.

Last for Boots and Shoes.

JOSIAH H. NOYES OF ABINGTON, MASS.

Letters Patent No. 729, dated March 19, 1861.

SPECIFICATION.

TO ALL PERSONS TO WHOM THESE PRESENTS SHALL COME:

Be it known, that I, JOSIAH H. NOYES of Abington, in the county of Plymouth and State of Massachusetts, have invented certain new and useful improvements in Lasts for Boots and Shoes, and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

The figures of the accompanying plate of drawings represent my improvements. Fig. 1 is a plan or top view of my improved last.

Fig. 2 is a central longitudinal vertical section of the same.

Fig. 3 is similar section of a view of a last made of a somewhat modified form.

Fig. 4 is a view of the last opened, or the parts separated.

In the manufacture of boots and shoes, the frequent removal of the last from the "upper," is rendered necessary; this is especially the case in the more modern mode of operation, where the sole is sewed by machinery to the "upper," which necessitates the very frequent removal and insertion of the last.

The lasts, heretofore used, have been so constructed, that they could not easily be taken out of the boot or shoe, without straining and injuring the upper. My improvements consist in forming the last in two pieces, so that the front and heel portions of the last can be separated from, or fastened to, each other; this arrangement being made by cutting the last transversely in such a manner that the two

Noyes's Improved Last for Boots and Shoes.

parts can readily and quickly be fastened together or disconnected, and yet hold firmly together and prevented from wabbling when so fastened.

In the accompanying drawings, the last *a a b b* is represented as divided at or near the shank transversely. In figs. 1, 2, and 4, the rear portion *b b* of the last is formed with a wedge-shaped tongue *c c*, that fits into a corresponding groove *e e*, so as to form a dove-tailed joint, which prevents all lateral motion, or "wabbling," when the portions *a a b b* are fastened together. To prevent any up and down play between the front and rear portions of the last, I employ a slotted sliding plate *f f*, travelling over set screws *g g* on the rear portion *b b*, and fitting under a lip *h* fixed to the front portion *a a*. The engagement, or disengagement, of the two last, is effected by slipping the tongue *c c* vertically in or out of its groove *e e*. The plate *f f* is moved forward so as to engage with the lip *h*, and then fastened by the set screw *g g*, when the last is to be inserted in the boot, or shoe. The last can readily and quickly be taken out of the upper, without injuring or straining the same, simply by loosening the set screws *g g*, sliding back the plate *f f*, and then inserting a hook and pulling out the rear portion *b b*, which, by means of the arrangement of the tongue *c c*, travelling in the groove *e e*, can thereby be easily removed from the boot or shoe. The front portion *a a* is then of course perfectly free to be taken out. A substantially similar arrangement, though a modified form of my improvement, is represented in fig. 3, in the transverse cutting of the last, instead of being in one straight line, forms an angular joint *i i*, the tongue *k k* fitting into the grooves *l l* to prevent the lateral play of the parts, and the up and down movement prevented by a set screw *m*; the removal of the last is effected in the same manner as in the first instance, by pulling vertically on the heel portion of the last, after loosening the screw *m*.

Having thus described my improvements, I shall state my claim as follows: What I claim as my invention, and desire to have secured to me by Letters Patent, is, in a last formed in two parts by cutting it transversely at, or near the shank. I claim the dove-tailed groove, and tenon joint as described, in combination with the slotted sliding plate, and set screws on the one section and the lip fixed upon the other section of the last, the whole being constructed and arranged, so as to operate substantially in the manner set forth. Whereby, while the parts may be disunited at pleasure, all lateral play is prevented when united.

JOSIAH H. NOYES.
